UNITED STATES PATENT OFFICE

PAUL A. NELSON, OF DENVER, COLORADO, ASSIGNOR, BY MESNE ASSIGNMENTS, TO THE GARDNER-DENVER COMPANY, OF QUINCY, ILLINOIS, A CORPORATION OF DELAWARE

DRILL SHARPENER

Application filed September 14, 1926. Serial No. 135,437.

The present invention relates to drill sharpeners, so-called, or in other words, apparatuses for shaping and sharpening drill steel and like instruments. The object is to provide a machine of a relatively simple character that is relatively light in weight, so that it can be easily transported and is simple in construction and effective in operation.

In the accompanying drawings:

10 Figure 1 is a rear elevation of the preferred embodiment of the invention,

Figure 2 is a top plan view of the same,

15 Figure 3 is a side elevation, showing the machine removed from its base and incidentally indicating that it may be mounted on a bench or other support,

Figure 4 is a vertical sectional view, and

15 Figure 5 is also a vertical sectional view taken at right angles to Figure 4.

20 In the embodiment disclosed, a base 6 is provided, which constitutes the lower head of a cylinder 7. This cylinder 7 has an upper head 8 preferably integral with the cylindrical wall, and formed on said upper head 8, 25 and preferably though not necessarily integral therewith, is an overhanging yoke, consisting of side arms 9 and an upper cross head 10. The cross head 10 has in its under face a recessed seat for a clamping die 12, which die 30 is preferably held in place by a bolt 13 extending transversely through the cross head 10.

In the cylinder 7 is located a vertically reciprocating piston 14 having an upstanding integral extension 15 that passes through a circular opening 16 formed in the head 8, the opposite sides of the extension operating in guideways 17 formed in the inner sides of the side arms 9. The extension is provided in its 40 upper side with a recessed seat 18 that receives a movable die 19 held in place by a clamping bolt 20, the die 19 thus moving upward into coaction with the die 12 upon the elevation of the piston 14 and movable downward out of such coaction. The piston 14 and extension 15 are preferably held against rotation in the cylinder by a tubular guide pin 21 that has a sliding fit in a socket 22 formed in the cylinder head 8. This guide pin has a reduced 45 extension 23 that is engaged in the piston 50

and is secured in place by a nut 24. The guide pin is also provided with vent ports 25 opening into the bore and into the interior of the cylinder, so as to permit air to flow freely into and out of the socket 22, accordingly as the 55 pin moves downwardly or upwardly.

Located on one side of the cylinder and preferably formed integral therewith is a bracket 26 on which is mounted a suitable dollying hammer 27, the dolly 28 of which is 60 adapted to be struck by the piston hammer 29 and thus operate on the work clamped by and between the dies 12 and 19.

For the purpose of supplying motive fluid to the cylinder 7 to operate the piston 14, and 65 to the dollying hammer 27 in order to operate on the dolly 28, the following mechanism is preferably employed. A valve casing 30 is mounted on one side of the bracket 26 and is provided with a tubular bore 31, into one end 70 portion of which fluid under pressure is supplied through a suitable hose connection 32 and port 33, as will be clear by reference particularly to Figures 2 and 3. At the right of the inlet or supply port 33 there is an internal 75 annular groove 34, from which leads a pipe 35 that conducts motive fluid from the passageway 36 in the base 6, and this passageway opens into the lower end of the cylinder 7 below the piston 14, as clearly shown 80 in Figure 4. To the right of the groove 34 is another internal groove 37, from which leads a conduit 38, supplying motive fluid to the dollying hammer in a manner well understood. A reciprocating plunger valve 39 85 operates in the bore 31, and has an annular groove 40 that is always in communication with the supply port 33. This groove is formed between end heads 41 and 42. The end head 42 is provided with an exhaust port 90 43 opening into the right hand end of the bore 31. The head 42 obviously traverses the grooves 34 and 37, and consequently the channel 40 in which the live fluid is located, may be brought into communication successively 95 with the grooves 34 and 37 upon the movement of the valve to the right. Any suitable means may be employed for effecting the operation of the valve. Thus in Figure 2, there is illustrated a handle crank 44, having a link 100

connection 45 with the said valve. The cylinder 7 above the piston 14 is vented to atmosphere through a port 46.

The operation of the structure is as follows. Assuming air under pressure is supplied to the chamber 40 of the valve casing and valve, if the valve is in the position shown in Figure 4, this live fluid is cut off from both the cylinder 7 and the dollying hammer 27. If now the valve 41 is moved to the right, the chamber 40 will first be brought into communication with the groove 34, whereupon the motive fluid will flow through the pipe 35 and passageway 36 into the cylinder 7 below the piston, thereby elevating the piston and causing the die 19 to move into coaction with the die 12. It will thus clamp a drill steel or other article placed between the dies. A further movement of the valve will cause the chamber 40 to be brought into communication with the groove 37, whereupon motive fluid will find its way to the dollying hammer 27 to cause its operation, so that the dolly will be hammered against the end of the drill steel or other article. When the operation has been completed a reversal of the valve will first cut off the motive fluid to the dollying hammer and then cut off motive fluid to the cylinder 7, the motive fluid in said cylinder below the piston being permitted to exhaust through the passageway 36, pipe 35, port 43, and the right hand end of the bore 41, to atmosphere. The piston will thereupon drop, releasing the work.

From the foregoing, it is thought that the construction, and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. In a machine of the character set forth, the combination with a cylinder member having an upper head and a yoke overhanging the head, of a piston in the cylinder member having an upstanding die carrier operating in the yoke, means for securing an upwardly faced die on top of the carrier and a downwardly faced die on the top of the yoke, a bracket at one side of the cylinder member, means mounted on the bracket for operating on work clamped by the dies, a valve mechanism mounted on the bracket, means for directing motive fluid from the valve mechanism to the cylinder member below the piston to raise the lower die into coaction with the upper die and to the means mounted on the bracket, the interior of said cylinder member above the piston being at all times open to atmosphere.

2. In a machine of the character set forth, the combination with a cylinder member having an upper head and a yoke overhanging the head, of a piston in the cylinder member having an upstanding die carrier operating in the yoke, means for securing coacting dies to the carrier and yoke, said cylinder member head having a socket and an upstanding tubular pin carried by the piston and slidably fitted in the socket, the bore of the pin having communication with the interior of the cylinder member above the piston and said interior having open communication with atmosphere.

3. In a machine of the character set forth, the combination with an upright cylinder, of a piston in the cylinder having a portion projecting therefrom, coacting clamping dies, one of which is carried by the projecting portion of the piston, a bracket at one side of the cylinder, fluid operated means mounted on the bracket for operating on work clamped by the dies, a valve mechanism mounted on the bracket, said bracket and valve together being narrower than the diameter of the cylinder, and means for directing motive fluid from the valve mechanism to the cylinder and to the fluid operated means on the bracket.

4. In a machine of the character set forth, the combination with an upright cylinder, of a piston in the cylinder having a portion projecting therefrom, coacting clamping dies, one of which is carried by the projecting portion of the piston, a support for the other die mounted on and located over the cylinder, a bracket at one side of the cylinder, fluid operated means mounted on the bracket for operating on work clamped by the dies, a valve mechanism mounted on the bracket, said bracket and valve together being narrower than the diameter of the cylinder, an actuating handle mounted on the upper die support and connected to the valve, and means for directing motive fluid from the valve mechanism to the cylinder and to the fluid operated means on the bracket.

In testimony whereof, I affix my signature.

PAUL A. NELSON.
